Patented Oct. 12, 1971

222,227

GRIPPING TOOL

John W. Rusztowicz, P.O. Box 116,
Utica, Mich. 48087

Filed May 15, 1970, Ser. No. 22,997

Term of patent 14 years

Int. Cl. D8—05

U.S. Cl. D8—51

FIG. 1 is a perspective view of the gripping tool;
FIG. 2 is a side view of the gripping tool of FIG. 1;
FIG. 3 is a top view of the gripping tool of FIG. 1;
FIG. 4 is a front view of the gripping tool of FIG. 1;
and

FIG. 5 is a rear view of the gripping tool of FIG. 1.
I claim:

The ornamental design for a gripping tool, substantially
as shown and described.
